(57) CLAIM

I claim the ornamental design for a shoe upper, as shown and described.

DESCRIPTION

FIG. 1 is a perspective view of a shoe upper showing my new design.

FIG. 2 is a front view thereof.

FIG. 3 is a rear view thereof.

FIG. 4 is a right side view thereof.

FIG. 5 is a left side view thereof; and,

FIG. 6 is a top view thereof.

The broken lines immediately adjacent to the photographic areas in FIGS. 1 through 6 define the bounds of the claimed design of the shoe upper, and form no part of the claimed design. The broken lines in FIGS. 1 through 6 showing the remainder of the shoe are for environmental purposes only, and form no part of the claimed design.
